UNITED STATES PATENT OFFICE.

GUIDO SAGRAMOSO, OF MILAN, ITALY.

ELECTRIC FURNACE.

Application filed May 19, 1924, Serial No. 714,480, and in Italy May 28, 1923.

The present invention relates to an improved electric furnace for melting and refining metals and metal alloys and especially steel, and has for its object to reduce the wear 5 of the electrodes to a minimum by protecting their whole length from the current supply terminals to the inner surface of the furnace arched ceiling from contact with the outer air and by maintaining them in cooled condition so as to counteract the effect of the 10 hot gases in the crucible.

A further object is to increase the efficiency of the operation and to insure that the operation will take place under the most favourable 15 conditions, by protecting the furnace charge from the action of the outer air.

Further objects of the invention are to render the charging of the furnace easier and more expeditious and in particular to enable 20 the charging with pieces of large sizes; permit the use of several crucibles having a different kind of lining according to the different kinds of material under treatment and according to the different stages of the treatment; render it possible to subject the 25 furnace charge to thermal or chemical actions prior to or after the electric treatment for which the furnace is built; and to facilitate the renewal of the crucible lining.

30 In the annexed drawings are schematically shown the constructive elements embodying the invention.

Figs. 1 and 2 are an external view and section respectively.

35 Fig. 3 shows the electrode support in section.

The furnace essentially comprises the crucible and the furnace operating means.

The crucible —*a*— consists of a cylindrical 40 or prismatic shell or container made of sheet iron, cast iron plates, or cast steel plates, the container being internally lined with refractory material and provided with one or more doors —*b*— as well as with a pouring spout —*c*—.

The upper portion of the container is closed by an arched roof or ceiling —*d*—; the container is carried on four wheels —*e*— which permit of its being displaced on a track —*f*—, the displacement being effected 50 either by hand or mechanically through a winch, screw-spindle, rack and pinion, an hydraulic cylinder or other device.

The furnace operating means comprise primarily two cradles —*g*—, whose top face 55 carries a portion of the track —*f*—, while

the bottom which has the form of a segment can rock—with or without interposed rollers, or other friction reducing device—on the cradle carriers —*h*— (which may either be curved or straight) and is secured to the foundations. The rocking of the cradle is effected by means of a lever —*z*— actuated by a screw spindle or other device. The said rocking movement of the crucible permits the pouring of the molten metal and 60 slags.

To the outer face of the cradles or to brackets fixed thereto are secured the iron uprights —*l*— serving to guide and support the horizontal crossbeams —*m*— by which the electrodes —*n*— are carried. The weight 70 of the crossbeams and electrodes may be balanced by counterweights —*o*—.

The vertical displacement of the crossbeams, and therewith of the electrodes, is 75 operated by screw spindles or fitted up between the uprights —*l*—.

On the top face of the cross beams —*m*— rest the brass terminals —*p*—, which grip the electrodes and supply them with current 80 by means of horizontal bars and flexible cables.

The electrode passes down through the metal jackets —*q*— suspended from the cross beams —*m*—, along with which they can be 85 slid up and down in the bells —*r*—. The jackets —*q*— are perfectly tightly fitted in the bells —*r*—, and both are double-walled and constantly cooled by circulating water.

The length of the jackets —*q*— and bells 90 —*r*— is such that the electrodes can be lowered till they touch the lowest level of the metal bath or raised till they touch the inner surface of the crucible ceiling and yet remain constantly enclosed in their envelope, 95 where they are protected against all contact with the outside and cooled so as to avoid the action of the hot crucible gases.

The bells rest on the furnace roof in sand-sealed circular grooves; and are carried by 100 an horizontal cross beam —*j*— which can be secured to the crossbeams —*m*— by means of hooks or other connecting devices as indicated at —*s*— in Fig. 1 and raised along with the latter when it is desired to free the crucible from the superincumbent structures in order to remove it from the electrode framing either for renewal of the refractory lining or for introducing into it the material 105 to be melted or refined and especially steel 110

blocks, large scraps or large unsuccessful castings and the like that could not get through doors —b—.

It is to be pointed out that in the event 5 of damage to the jackets —q— or bells —r—, temporary lack of cooling water or the like, the furnace, after removal of the jackets and bells, can continue working with bare electrodes as are at present employed in most 10 of the other furnaces.

As to the crucible, due to the fact that it is independent from the electrical equipment and removable, more than one crucible can be kept, in readiness either for avoiding interruption 15 of work when the refractory lining must be renewed or in order to permit working with different kinds of lining (acid, basic or neutral) according to the different materials to be treated and to the different stages 20 of the treatment, or finally in order to subject the crucible contents to thermal or chem-

ical actions other than those determined by the electric current.

Having now particularly described and ascertained the nature of my said invention 25 and in what manner the same is to be performed, I declare that what I claim is:—

An electric furnace, a support therefor, a pair of vertical standards mounted on said support, a crossbeam, adjustably mounted 30 on said standards, an electrode secured to said crossbeam and movable therewith, a double walled jacket secured to said beam and surrounding said electrode, a double walled bell adapted to be supported by said 35 furnace surrounding said jacket and within which said jacket is adapted to slide, and releasable means to connect said bell with said beam whereby said electrode, said jacket and said beam can be elevated with respect to 40 said furnace.

GUIDO SAGRAMOSO.
